WINDOW SASH BALANCE

Abraham Morrison, Detroit, Mich., assignor to
 Annie Lillian Morrison and Ida Morrison, Detroit, Mich.

Application March 30, 1944, Serial No. 528,708

6 Claims. (Cl. 16—198)

My invention relates generally to spring sash balances and specifically to improvements in a housing for the spring and in the drum containing the spring, as well as improvements in other related parts, hereinafter more fully described and claimed. By my invention I seek to provide a simpler, more durable sash balance that is easily assembled, smooth running, quietly operating, practical in use, and inexpensive to manufacture, assemble, and install. It is understood that minor changes may be made in my invention without departing from the real character of it.

The preferred form of construction by which these objects are attained is shown in the accompanying drawing in which:

Figure 1 is a sectional side elevation of the assembled balance with the side cover plate 19 removed.

Figure 2 is a section taken on line 1—1 of Figure 1.

Figure 3 is a plan view of Figure 1 with the side cover plate shown in section.

Figure 4 is a vertical section of side cover plate 19.

Figure 5 is an outside view of slotted spring holder and connector tube 11.

Figure 6 is an end view of connector tube 11. The same reference numerals refer to the same parts throughout the several views.

My device consists of an angle plate 1, having a lower flange 23 and a wall portion including an offset portion 2 extending laterally therefrom to form a more effective locking means. Lower flange 23 has an offset portion 23', extending downwardly the extent of the thickness of the steel in said flange, as shown, to provide clearance for easy installation in and fastening to the window frame. This novel construction of flange 23 will eliminate the two impractical methods now necessarily employed with straight flanges in fastening sash balances to the casement. The first of these methods is to chisel space in the casement to receive the flange end which remains on the outside for fastening. This is time consuming, and it is costly to the one installing balances since he is usually paid per balance installed. The second method is to draw that flange end up to the casement against strain to permit it to be screwed in place. This means is equally unsatisfactory because a screw thus inserted can in time, with the balance in operation, become loosened and throw the entire balance out of working position. My improvement in offsetting flange 23 as indicated permits

the housing to fit farther into the casement opening, thereby bringing both ends of the flange on a level for fastening without added effort.

6 A second plate 4 having a wall portion and a lower flange 22 is secured to the angle plate by welding the respective lower flanges of each plate as shown at 24. A wall of paper 3 with a center aperture is placed between plates 1 and 4 to provide space for extension hub 5 of plate 4. When plate 4 is secured to plate 1 by bolt 9 which is tightened by nut 12, and when lower flange 22 of plate 4 is spot welded to lower flange 23 of plate 1 at spots 24, plate 1 and thereby the housing is strengthened at all points. Bolt 9 is not provided with a screw driver slot at its head, the reason being to discourage any attempt at opening the housing at that end, because it is intended that bolt 9 and nut 12 remain a permanent fixture in the housing. Plate 4 serves to complete the locking of the housing since it conforms to the inner contour of cover plate 19, thus preventing sliding movement.

Slotted spring holder and connector tube 11 fits into extension hub 5 of plate 4 and is riveted through said extension hub and through plate 1 by extension lugs 10 of connector tube 11.

Tape drum 7 which is mounted on connector tube 11 has an outside extension sleeve 8 which serves to frictionally oppose the rotation of the drum and keep it in free rotating position, while at the same time providing a flush inside wall for even winding of the spring 13. A washer 6 is fitted over extension sleeve 8 of tape drum 7 to separate the drum from plate 4 in order that the drum 7 may have room to rotate freely on slotted spring holder and connector tube 11. A spring 13 is mounted in tape drum 7 over spring holder 11, its inner end 21 being hooked through slot 14 of spring holder 11, while its outer end 25 is hooked over projection 15 pressed inward in the outer rim of tape drum 7. Then one end of steel tape 18 is threaded through holes 16 in the outer rim of tape drum 7 and folded over to 35 form a fastening as shown, while the other end leads through opening 17 provided in the lower flanges of plates 1 and 4, and is then hooked to the window sash (not shown).

This entire assembly is covered by cover plate 50 19 which has a projection 20 on its lower ends to engage the offset portion 2 of plate 1 to prevent upward movement. Ferrel 26 which has a screw driver slot on its head and is threaded to fit over bolt 9, passes through a suitable center opening in cover plate 19 and is screwed on to

bolt 9 thereby completing the assembly. This means of securing the cover plate to the angle plate is an improvement over the present method of fastening the cover plate by riveting extension lugs which are made to project from the connector tube through the cover plate for that purpose. The present method does not permit easy removal of the cover plate for oiling or repairs to the inner parts without permanently damaging the cover plate and possibly related parts as well. My improvement takes care of this by allowing the cover plate to be easily and effortlessly removed by simply unscrewing ferrel 26, while with ferrel 26 in place, the cover plate remains firmly secured to the rest of the housing.

Having thus fully described my invention, I claim:

1. In a sash balance a housing comprising an angle plate having a lower flange and a laterally extending wall portion including an offset portion adjacent the lower flange; an inner plate secured to said angle plate; a cover plate which has a projection on its lower ends to engage the offset portion of the angle plate, preventing upward movement, said inner plate conforming to the inner contour of the cover plate to prevent sliding movement.

2. In a sash balance a housing comprising an angle plate having a lower flange and a laterally extending wall portion including an offset portion adjacent the lower flange; a wall of paper fitted to said angle plate and having a center opening for the purpose of receiving the offset portion of an inner plate; an inner plate secured to said angle plate; a cover plate which has a projection on its lower ends to engage the offset portion of the angle plate, preventing upward movement, said inner plate conforming to the inner contour of the cover plate to prevent sliding movement.

3. In a sash balance a housing comprising an angle plate having a lower flange and a laterally extending wall portion including an offset portion adjacent the lower flange; a wall of paper fitted to said angle plate and having a center opening for the purpose of receiving the offset portion of an inner plate; an inner plate offset at its center to receive the outwardly projecting hub on the back of a tape drum; a tape drum; a cover plate which has a projection on its lower ends to engage the offset portion of the angle

plate, preventing upward movement, said inner plate conforming to the inner contour of the cover plate to prevent sliding movement.

4. In a sash balance a housing comprising an angle plate having a lower flange and a laterally extending wall portion including an offset portion adjacent the lower flange; a wall of paper fitted to said angle plate and having a center opening for the purpose of receiving the offset portion of an inner plate; an inner plate offset at its center to receive the outwardly projecting hub on the back of a tape drum; a tape drum having an outwardly projecting hub extending from its center back wall for the purpose of frictionally opposing the rotation of the drum to keep it in free rotating position; a cover plate which has a projection on its lower ends to engage the offset portion of the angle plate, preventing upward movement, said inner plate conforming to the inner contour of the cover plate to prevent sliding movement.

5. In a sash balance a housing comprising an angle plate having a lower flange and a laterally extending wall portion including an offset portion adjacent the lower flange; a lower flange offset at one end to provide clearance for easy installation in and fastening to the window frame; an inner plate secured to said angle plate; a cover plate which has a projection on its lower ends to engage the offset portion of the angle plate, preventing upward movement, said inner plate conforming to the inner contour of the cover plate to prevent sliding movement.

6. In a sash balance a housing comprising an angle plate having a lower flange and a laterally extending wall portion including an offset portion adjacent the lower flange; an inner plate secured to said angle plate; a bolt passing through center openings in the angle plate and the inner plate, and tightened by a nut; a nut; a cover plate which has a projection on its lower ends to engage the offset portion of the angle plate, preventing upward movement, said inner plate conforming to the inner contour of the cover plate to prevent sliding movement; a ferrel having a screw driver slotted head and threaded on the inside, passing through the cover plate and on to the bolt to so secure the cover plate that it can be easily removed when needed.
